UNITED STATES PATENT OFFICE.

EDWARD A. McMILLIN, OF NORTH ADAMS, MASSACHUSETTS.

BINDING-STRAP BUCKLE.

1,235,827.

Specification of Letters Patent. Patented Aug. 7, 1917.

Application filed July 10, 1914. Serial No. 850,129.

To all whom it may concern:

Be it known that I, EDWARD A. McMILLIN, a citizen of the United States of America, residing and having my post-office address 5 at the city of North Adams, in the county of Berkshire and Commonwealth of Massachusetts, have invented certain new and useful Improvements in Binding-Strap Buckles, of which the subjoined description, in connection with the accompanying drawing, 10 constitute a specification.

This invention relates to that class of fastenings for bundles, packages, &c., in which the articles to be secured are assembled either 15 with or without an external wrapper or covering and are confined or held against separation by means of a tape, strap or the like passed around them or the receptacle in which they are held, and one end of the strap 20 is connected with the other end by means of a device in the nature of a buckle to which both ends of the strap are connected in such a way that by drawing one end of the strap through the buckle and strap-holding devices 25 the strap is seized and firmly held against back-slip or loosening.

The main object of the invention is to provide a fastening device which will firmly hold the strap tightly drawn up without the 30 aid of any spurs or prongs to penetrate the leather, tape or web of which the strap may be composed.

The invention is fully set forth in the accompanying drawings wherein Figure 1 is 35 a plan view of my invention as the fastening devices appear when tightened up as when in use. Fig. 2 is a longitudinal section taken through the center of the strap and buckle parts on the line 2—2. Fig. 3 is a plan view 40 of the coupling jaw. Fig. 4 is a like plan of the binding jaw. Fig. 5 is a sectional view of the articulated jaws as straightened out to grasp and hold the strap. Fig. 6 is a like view of the same parts with the binding jaw raised to break the grip and release the strap. Fig. 7 is a plan view of a 45 sheet plate blank from which the coupling loop is struck up. Fig. 8 is a plan view of the core plate of the coupling loop. Fig. 9 is an edge view of the core plate showing an over-fold along its straight edge.

The constituent parts of the invention 50 comprise three preferably metallic members, viz., a metallic coupling loop or stirrup C, which is permanently fastened to one end of the tape or strap W, binding jaw A, and

a coupling jaw B, both of which can be slipped off the strap or tape when the coupling member is disconnected from the loop C. In use the three metallic members are 60 interconnected by the strap W alone.

The coupling loop C, is composed of an outer coupling plate 17, and an inner core-plate 51, Fig. 8. The coupling plate 17 is folded transversely upon itself along the 65 middle line 52, so that the two leaves shall register as to their marginal edges, thus leaving the edge of the plate flush all around. The office of the core plate is to stiffen the loop, and the edge of the fold supplies a rounded 70 surface over which the strap or band W is carried and which will not chafe or abrade the band. The coupling plate is first punched out in the shape shown in Fig. 7, the metal on each side of the crossbar 18, being 75 punched out leaving openings instead but leaving the crossbar 18 as seen in Fig. 7. This blank is then passed to a press where it is transversely folded upon itself along the center of bar 18 which leaves it in the 80 form seen in Fig. 1, with two rivet holes punched, one in each leaf. The parts are assembled and the loop finished by first folding one end of the strap or band over the folded end 55 of the core plate, carrying one 85 end of the band back flush with the rear edges of the leaves of the core plate with cement or glue between them. Then the core plate and band, so combined, are slipped 90 between the leaves of the coupling plate, care being taken that their margins are kept in apposition. Then the assemblage goes to a press which inserts a rivet R, through the rivet holes in the leaves of both plates and the whole is headed down firmly. In this 95 operation it will be seen that the strap or band will be held firmly between two outside plates and the interposed core plate.

The coupling jaw B is punched and swaged from steel or other metallic plate 100 into substantially the form shown in Fig. 3. The body part 8 has a wide projecting tongue 9 which is bent over into the form of a hook to hook over the coupling bar 18 of the loop 17. It has two side parts 10, 10, 105 from the outer edge of each of which a small journal stud or pintle 13 projects, which in service finds lodgment in the horse shoe shaped bearings 3, 3, of the clamping jaw A. It will be noticed that these pintles are substantially smaller than the inside dimensions 110 of the bearings 3, 3. This disparity of de-

sign and proportion of the coöperative parts is to enable the pintle in changing its seat when the draft on the strap or its relaxation tends to draw the coupling jaw into an altered position. This disparity also allows the jaws to accommodate themselves to the use of straps or bands of diverse thicknesses. The jaw 11 is finished with rounded edge or corner 12 wherever the strap bears upon or is 10 strained over it whereby chafing or abrasion of the strap is avoided.

The binding jaw is shown in plan in Fig. 4 and in edge elevation in Fig. 2. This and its companion member B, are punched or 15 swaged out of steel or other metallic plate of suitable thickness and strength. It is formed with a broad thumb-piece 5 by which it may be lifted or rotated about the pintles 13, 13. It has a narrow marginal portion 15, 15, at 20 either side, the ends of which are connected by the clamping jaw 7. The upper outer edge of this jaw is rounded as at 4, Fig. 5, which in the clamping function engages one side of the strap and crowds it against a 25 similar edge 12 of jaw 11, Fig. 5. The parts 15 are bent around into horseshoe shape to provide free open bearings 3, 3, to receive a pintle on each end of the coupling jaw B. The transverse space between the parts 15, 30 15, is wide enough to permit the coupling jaw to turn freely therein when the pintles are seated in the bearings 3, 3.

The buckle is used as follows:

Let the jaw A be placed in the position 35 shown in Fig. 4 and let the jaw B be inverted so that the hook 9 will be turned under and pointed to the right. Then drop the hook 9 over bar 7 of jaw A. Next turn jaw B up so that it will drop through gap O, of 40 jaw A, until its pintles 13, 13, rest in the bearings 3, 3, of jaw A. Then roll the hook to the left until it is brought up to a level. These manipulations properly couple the two 45 members and leave the pintles seated in the bearings 3, 3, ready to receive the strap or band W. This is then threaded in as follows:—The parts being coupled as in Fig. 2, the strap is passed around the bundle or package, the loop C being brought up to the 50 upper side of the same, then the free end W' is passed under the thumb-pad 5, of jaw A, up through gap O of jaw A and up through, gap OO of jaw B to the left of gripping bar 7, over bar 7, down under bar 55 11 of jaw B and thence out through gap O and under thumb-pad 5 where it can be seized by the operative. This leaves the strap involved between the bars 7 of one jaw and 11 of the other where it can be gripped 60 by pressing down pad 5. By raising the pad the grip on the strap will be released when by stretching the end W' of the strap its binding tension will be increased and this increased tension may be secured by turning 65 the pad 5 down which clamps the bars 7 and

11 tightly together with the strap tightly clamped between them.

I therefore claim as my invention and desire to protect by Letters Patent, the following:

1. In a device of the character described, the combination of a coupling member having at one end a part to engage a member to be coupled and at its opposite end an offset gripping jaw, said coupling member having a transverse recess adjacent said jaw, and a clamping member having at one end an offset gripping jaw and side arms separated from one another by an unobstructed space to receive the gripping jaw of the coupling member, and pintles projecting outwardly 70 from the sides of the coupling member adjacent the offset jaw thereof and adapted to loosely engage the clamping member at the point of connection between the jaw and 75 sides of the latter.

2. In a device of the character described, the combination of a coupling member comprising a body part offset at one end to provide a coupling hook and having side arm 90 extensions at the opposite end connecting with an offset gripping jaw, which latter is separated from the body part by an unobstructed space, and a clamping member comprising a body part, side arm extensions 95 and an offset gripping jaw, the side arm extensions being separated from one another by an unobstructed space wider than the width of the coupling member whereby to receive in 100 said space the jaw of the coupling member, said clamping member having at its end opposite the jaw thereof a finger engaging part, and a detachable pivotal connection between the side arms of the coupling and 105 clamping members.

3. In a device of the character described, the combination of a coupling member comprising a body part offset at one end to provide a coupling hook and having side arm 110 extensions at the opposite end connecting with an offset gripping jaw, which latter is separated from the body part by an unobstructed space, and a clamping member comprising a body part, side arm extensions and an offset gripping jaw, the side arm 115 extensions being separated from one another by an unobstructed space wider than the width of the coupling member whereby to receive in said space the jaw of the coupling member, and outwardly projecting pintles 120 on the side arms of the coupling member adapted to loosely engage the clamping member adjacent the jaw thereof to form a pivotal connection between the members.

4. In a device of the character described, 125 the combination of a clamping member having a finger engaging part at one end and a return bent gripping jaw portion at the opposite end, the jaw portion being separated from the body part of the member by 130

an unobstructed space, and a coupling member having at one end a coupling part and at its opposite end a return bent gripping jaw part separated from the body portion thereof by an unobstructed space, the width of the coupling member being less than the width of the space of the clamping member whereby the gripping jaw of the coupling member may be positioned in said space to permit the jaws of the respective members to grasp a strap or the like therebetween, and outwardly projecting pintles on the sides of the coupling member of a width to overlie and engage the clamping member at the point of connection between the gripping jaw and the body of the clamping member.

5. In a fastener device of the character described for bands or the like, the combination of a metallic part adapted to be secured to one end of the band, said metallic part having a loop portion, of a coupling member having at one end an offset hook

part to engage said loop portion and having at its opposite end a return bent gripping jaw part separated from the body portion thereof by an unobstructed space, and a clamping member having an operating finger piece at one end and a return bent gripping jaw at its opposite end separated from the body portion of the clamping member by an unobstructed space adapted to receive the gripping jaw of the coupling member, and said coupling member having side projecting pintles adapted to loosely engage the clamping member at the point of connection between the gripping jaw and the body portion thereof.

In testimony whereof I have hereto subscribed my name this sixth day of July, A. 40 D., 1914.

EDWARD A. McMILLIN.
